RADIO RECEIVER

Howard Corey Lawrence, Jr., Haddonfield, N. J.,
assignor to Radio Corporation of America, a
corporation of Delaware

Application April 24, 1943, Serial No. 484,365

7 Claims. (Cl. 250—20)

This invention relates to radio receivers and more particularly to noise limiting and the prevention of overloading effects in continuous wave receivers which are not equipped with automatic volume control.

Receivers intended for use with radio beacons arranged to emit keyed signals are ordinarily not provided with automatic volume control. This is also true of receivers used with radio direction finders and in other applications where in the variations in received signal strength must be depended upon for providing the required indication or information. In a direction finder, for example, provided with a rotatable directive antenna, the received signal strength varies as a function of the alignment between the antenna and arriving wave front. If such an antenna is operated with a receiver provided with automatic volume control, the receiver tends to produce constant output regardless of variations of the strength in the received signal, so that as the antenna is rotated no sharp variation in receiver output will occur and no indication, or a very broad indication, of the direction of the wave front will be given.

However, some form of volume control is essential in substantially any radio receiver to limit noise and to prevent saturation or overloading when the receiver signal strength exceeds the capabilities of the receiver. This is particularly true of direction finders, beacon receivers and the like, since excessive overloading may cause the receiver output to decrease upon further increase in signal strength and increase upon decrease of signal strength, causing false bearing indications.

It is the principal object of the instant invention to provide an improved method of and means for preventing overloading effects and limiting noise in a radio receiver which is arranged for reception of keyed signals. This and other objects will become apparent to those skilled in the art upon consideration of the following description with reference to the accompanying drawing, of which:

Figure 1 is a schematic diagram of a portion of the circuit of a radio receiver embodying a limiter arranged in accordance with the invention.

Figure 2 is a modification of the system of Figure 1, and

Figure 3 is a graphical representation of the control characteristics of the systems of Figures 1 and 2.

Referring to Figure 1, a radio receiver 1 of the conventional superheterodyne type is arranged

with its last intermediate frequency amplifier tube 3 connected to a tuned circuit comprising a capacitor 5 and an inductor 7. This circuit is tuned to the intermediate frequency of the receiver 1 and is coupled through a capacitor 9 to a detector 11. The output circuit of the detector 11 is coupled in known manner to the usual audio amplifier and loud speaker or the like, not shown. A gaseous discharge tube 13 is connected across the tuned circuit elements 5 and 7. A resistor 15 may be provided in series with the tube 13 in order to modify the action of the limiter circuit, as explained more fully hereinafter. A transformer 17 is provided with a secondary winding 19 connected between the lower ends of the elements 5 and 7 and the return connection to the output circuit of the amplifier 3. The impedance of the winding 19 must be low compared to the resonant impedance of elements 5 and 7. The primary of the transformer 17 is connected to a beat oscillator 21.

The operation of the above described system is as follows:

As long as the amplitude of the output of the amplifier 3 is lower than the predetermined value, the gas in the tube 13 remains in an un-ionized state so that no conduction takes place through the tube 13. The beat oscillator 21 is tuned to a frequency differing from the intermediate frequency of the receiver 1 by a relatively low amount; for example, 1,000 cycles. The outputs of the amplifier 3 and beat oscillator 21 are applied in series to the detector 11. Keyed continuous wave signals applied to the grid of amplifier 3 are converted by the detector 11 to audio signals of a frequency equal to the difference in frequency between the beat oscillator and the intermediate frequency. When the output of the receiver 1 exceeds the predetermined amplitude, the gas in the tube 13 becomes ionized. It is a well known characteristic of gaseous discharge tubes that the terminal voltage of the tube remains substantially constant over a relatively wide range of tube current when the gas is ionized. Thus the voltage across the tube circuit 5, 7 cannot increase above a level determined by the characteristics of the tube 13. The amplitude of the output of the detector 11 is a function of the amplitudes of the IF output voltage of the receiver 1 and the voltage produced by the oscillator 21. Therefore, if the beat oscillator output has remained constant, the detector output will also remain at a constant level. It should be noted that the beat oscillator voltage is applied in series with rather than across the

tube 13. This is done in order to prevent the limiting action of the tube 13 from changing the output of the beat oscillator and removing the audio modulation established by the beat oscillator.

Referring to Figure 3, as the input voltage from the amplifier 3 increases, the output voltage will increase correspondingly up to the point 23. At this point the gas in the tube becomes ionized and further increase in input will produce little or no increase in output, as indicated by the solid line 25. Under some circumstances, it may be desirable to allow a further increase in output to take place even after the point of ionization of the tube 13 is reached. This may be accomplished by including the resistor 15 in the circuit of Figure 1. Then, as the current through the tube 13 increases with increase in input from the IF amplifier 3, the drop in the resistor 13 will increase proportionally, providing a resultant characteristic for both the gas tube and resistor, as illustrated by the dash line 27.

Figure 2 shows a modified circuit employing inductive coupling between the plate circuit of the intermediate frequency amplifier and the detector. Portions of the circuit of Figure 2 which correspond to the circuit of Figure 1 are designated by similar reference numerals. The plate circuit of the IF amplifier tube 3 may be connected to a tap 29 at an intermediate point on the inductor 7 to provide step-up by auto-transformer action of the voltage applied to the tube 13. A secondary winding 31 is inductively coupled to the inductor 7 and is arranged to be tuned to resonance by a shunt capacitor 33. The detector 11 comprises a diode connected in conventional manner to a load resistor 35 and coupled through a capacitor 37 to an audio frequency amplifier, not shown. The load resistor 35 is shunted by a capacitor 39 to by-pass intermediate frequency voltage around the resistor 35. The beat oscillator 21 is coupled through a transformer 17 to the cathode circuit of the diode 11. The operation of the system of Figure 2 is substantially the same as that of Figure 1.

Thus the invention has been described as an improved limiter for radio receivers intended for reception of keyed signals. A variable impedance having an amplitude limiting characteristic, such as a gaseous discharge tube, is connected across the plate circuit of the last intermediate frequency amplifier tube, and a beat frequency oscillator is connected in series with said gas tube. This arrangement allows the received signal and any noise which may arrive with it to be limited to a predetermined amplitude without removing the modulation produced by the beat frequency oscillator.

I claim as my invention:

1. In a radio receiver, means for providing carrier-frequency signal voltage, a gaseous discharge tube, means for applying said signal voltage to said gaseous discharge tube whereby said signal voltage is limited to a predetermined amplitude, detector means, an oscillator, and means for applying the output of said oscillator and the signal voltage across said discharge tube in series to said detector, whereby the amplitude of the output of said oscillator which is applied to said detector is not substantially limited by the action of said discharge tube.

2. In a radio receiver, means including an output circuit for deriving a carrier-frequency signal voltage, a non-linear impedance device connected to the output circuit of said means, a detector, an oscillator, and means for applying the output of said oscillator to said detector in series relationship with the voltage across said non-linear impedance device.

3. In a radio receiver including means for deriving a continuous wave signal voltage, a detector, a voltage limiter connected across said means, an oscillator, and means for applying the output of said oscillator in series with that across said limiter to said detector.

4. In a radio receiver including means for deriving a continuous wave signal voltage, a non-linear impedance device connected across said means, said non-linear impedance device including a gaseous discharge tube and a resistor connected in series therewith, an oscillator, a detector, and means for applying the output of said oscillator to said detector in series with said continuous wave voltage.

5. A radio receiver including at least one intermediate frequency amplifier tube, a resonant circuit connected to the anode circuit of said amplifier tube, a gaseous discharge tube connected across said resonant circuit, a local oscillator, a detector, and means for applying voltage appearing across said discharge tube and the output of said oscillator in series with each other to said detector.

6. A radio receiver system including an intermediate frequency amplifier tube, a resonant circuit connected to the anode of said amplifier tube, a voltage limiter connected across said resonant circuit, a detector, a local oscillator, and means for applying voltage appearing across said limiter and the output of said oscillator in series with each other to said detector.

7. The invention as set forth in claim 1 wherein said means for applying said signal voltage to said gaseous discharge tube includes voltage step-up transformer means.
